Primary Examiner — Janice Patyk*Assistant Examiner* — Kendra L Hebel(74) *Attorney, Agent, or Firm* — Batt IP A Law Corporation; Richard Batt(57) **CLAIM**

The ornamental design for a fry basket as shown and described.

DESCRIPTION

FIG. 1 is an upper front left side perspective view of a fry basket showing our new design;

FIG. 2 is a front view thereof;

FIG. 3 is a rear view thereof;

FIG. 4 is a right view thereof;

FIG. 5 is a left view thereof;

FIG. 6 is top view thereof; and,

FIG. 7 is a bottom view thereof.

The broken lines shown in the drawings show portions of the fry basket and form no part of the claimed design.
